Primary Examiner — Patricia Palasik(74) *Attorney, Agent, or Firm* — Dean W. Russell; Michael A. Bertelson; Kilpatrick Townsend & Stockton LLP**(57) CLAIM**

The ornamental design for a chisel holder, as shown and described.

DESCRIPTION

FIG. 1 shows a right side view of a tool, the left side view being a mirror image of the right side view.

FIG. 2 shows a front view of the tool of FIG. 1.

FIG. 3 shows a top view of the tool of FIG. 1.

FIG. 4 shows a front right isometric view of the tool of FIG. 1, a front left isometric view being a mirror image of the front right isometric view of FIG. 4.

FIG. 5 shows another front right isometric view of the tool of FIG. 1, a front left isometric view being a mirror image of the front right isometric view of FIG. 5; and,

FIG. 6 shows another front right isometric view of the tool of FIG. 1, a front left isometric view being a mirror image of the front right isometric view of FIG. 6.

The broken lines form no part of the claimed design.
